UNITED STATES PATENT OFFICE.

PERCIVAL W. MILES, OF WILKES-BARRE, PENNSYLVANIA.

SANDING DEVICE.

1,340,728.

Specification of Letters Patent. Patented May 18, 1920.

Application filed February 26, 1920. Serial No. 361,417.

To all whom it may concern:

Be it known that I, PERCIVAL W. MILES, a citizen of the United States of America, and a resident of Wilkes-Barre, in the county of Luzerne and State of Pennsylvania, have invented certain new and useful Improvements in Sanding Devices, of which the following is a specification.

This invention relates to track sanding apparatus and particularly to sand blowers for use on traction vehicles, such as street cars and railway cars.

An object of this invention is to provide novel means whereby sand is kept free of moisture and prevented from becoming clogged in the apparatus due to moisture or freezing, the said invention furthermore contemplating the provision of novel means whereby the sanding attachment may be applied to the floor of a car or under the vestibule of a car, while at the same time preventing the access of moisture to the sand.

A further object of this invention is to produce a sanding apparatus having the usual sand blowing feature, while at the same time it has a hand operated gate or valve which can be actuated, if for any reason the sanding apparatus is deprived of air to blow the sand, thus making it practical for use when the air producing apparatus of a train is impaired.

A further object of this invention is to produce a sand blowing apparatus having an air space which prevents moisture from reaching the sand by capillary attraction.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification, wherein like characters denote corresponding parts in the several views, and in which—

Figure 1 illustrates a vertical sectional view of a sanding device embodying the invention;

Fig. 2 illustrates a sectional view of the device on a line corresponding with the line 2—2 of Fig. 1;

Fig. 3 illustrates a sectional view of the device on a line corresponding with the line 3—3 of Fig. 1;

Fig. 4 illustrates a perspective view of a valve;

Fig. 5 illustrates a top plan view of the sand distributing device, and

Fig. 6 illustrates a sectional view embodying a modification.

In these drawings, 10 denotes a casing with a flange 11, adapted to fit against the under surface of the floor of a car, and said flange may be provided with apertures 12 through which fastenings may be extended to anchor the casing to the floor. The casing is preferably square, although it may be rectangular in cross section and its bottom is inclined toward the center and terminates in a spout 12, to which a hose or other pipe may be secured for directing sand to the track.

One wall of the casing has an aperture 13 therein for the reception of the air pipe 14, whereas the opposite wall has an aperture 15 to receive the shank 16 of the valve or gate 17 which is hand operated for the purpose of permitting the escape of sand from the sand box if the sand blower is not in operation.

The shank 16 has a coupling 18 with a bifurcated end 19 to which a link 20 is connected by the pivot 21 and the opposite end of the said link extends to a lever 22 or other means for reciprocating the gate. The gate or valve is held normally closed in the present embodiment of the invention by a spring 23 which has one end anchored to a permanent part of the car and the other end connected to the said lever, so that oscillation of the lever will result in opening or closing of the gate or valve, as will be apparent.

The sand controlling mechanism which is controlled within the casing, is held in such spaced relation to the casing as to permit free circulation of air to maintain the interior in a dry state while at the same time access to moisture is obviated.

The sand distributing mechanism comprises a hollow member 24 having the sides converging at the bottom to form a chute with an opening for the escape of sand.

The hollow member 24 has a flange 25 around its edge at the top and this flange has its edge lying in a seat 26 formed in the top of the casing.

The hollow member 24 has an upstanding flange 27 and there are upstanding flanges 110

- 28 at the outer edges of the flange 25 and there is a space between the flanges 27 and 28 for the circulation of air. The sand box 29, such as is usually employed in street rail- 5 way cars, has its discharge end projecting into the space formed by the flanges 27 so that sand from the sand box will find its way into the interior of the hollow mem- 10 ber 24.
- 10 The interior of the hollow member is divided transversely by a partition 30 which partition is of a depth equal practically to the depth of the unrestricted portion of the said hollow member, although the propor- 15 tions in this respect need not be strictly held. On one side of the partition 30 there is a floor or horizontally disposed partition 31 which however, does not fill the space within the compartment, but there is an opening 32 20 at the end of the said partition 31 for the escape of sand. The space above the partition 31 is provided with an inclined floor 33, which terminates at a point over the first mentioned partition 31, so as to direct sand 25 into the compartment toward that end of the partition 31 which is uninterrupted. The air pipe heretofore mentioned projects through a wall of the hollow member 24 and terminates just above the partition 31 where 30 the sand gravitates from the floor 33 and when air is delivered through the said pipe with sufficient force, it blows the sand through the opening at the end of the partition 31 and the said sand finds its way 35 through the opening in the bottom of the hollow member and is discharged into the casing and through the exhaust pipe thereof.
- The compartment on the opposite side of the partition 30 has an inclined bottom 34 40 which terminates short of one wall of the compartment to form a space for the passage of sand. Under the lower end of the inclined bottom, there are guides 35 one of which is attached to the inner wall of the hollow member and the other of which is attached to the partition 30 and these guiding members support the gate or valve which opens or closes the opening for controlling the sand. This is the hand opera- 45 tive valve or gate which is utilized when the sand blowing apparatus is inactive and can be manipulated as heretofore stated for permitting the escape of sand to the track. The gate or valve has an opening 36 to 50 permit the escape of any sand which might work its way between the end of the inclined bottom 34 and the said gate during its reciprocation.
- On the inside of the compartment which 60 is guarded by the gate is a beveled fillet comprising a series of strips 37 which may be secured to the inner walls of the said compartment, the said strips as stated, having beveled upper surfaces which prevent lodg- 65 ment of sand in the said compartment.

As stated, the device as so far described, is intended to be employed in connection with the floors of cars where the sand box is under the seats or otherwise located inside of the cars.

When the apparatus is to be used in conjunction with sand boxes which are under the vestibules of cars, the sand box is preferably guarded by a housing A which is practically of the same contour as the sand box, 70 but is larger than said sand box and the said housing may be secured to the under surface of the vestibule and extend downwardly. When this form of apparatus is employed, the sand blower forming the sub- 75 ject of this invention as heretofore described, is attached to the casing or housing A in the manner shown, whereas the discharge opening of the sand box is disposed so that it discharges into the hopper of the 80 apparatus and hence it would discharge or extend within the space bounded by the flanges 27 of this apparatus.

I claim:

1. In a sand blower, a casing having 90 means of attachment to a car floor, a hollow member suspended within the said casing, the said hollow member having compartments for the reception of sand, a valve for controlling one of said compartments, means 95 for actuating the said valve, a floor extending part way across the other compartment, an inclined floor extending over the opening of the interrupted lower floor, an air delivery pipe extending into the last mentioned 10 compartment in the space above the first mentioned floor and below the space at the end of the inclined floor.

2. In a sanding device for cars, a casing having means for delivering sand to a track, 10 a hollow member suspended in said casing and spaced therefrom, a flange on the hollow member adapted to be secured to the under side of a floor of a car, a flange on the hollow member extending through the floor, 11 compartments within the hollow member to which sand is delivered from the sand box of a car, and means for effecting the discharge of sand from the sand box to the hollow member.

3. In a sanding device for cars, a casing having means for delivering sand to a track, a hollow member suspended in said casing and spaced therefrom, a flange on the hollow member adapted to be secured to the under side of a floor of a car, a flange on the hollow member extending through the floor, compartments within the hollow member to which sand is delivered from the sand box of a car, means for effecting the discharge 12 of sand from the sand box to the hollow member, a partition dividing the hollow member into compartments, an inclined floor in one compartment terminating short of the wall of the compartment to form an 13

opening; a valve under the said opening, means for moving the valve into and out of registry with the said opening, a horizontal partition in the other compartment 5 terminating short of one of the end walls of the compartment, an inclined floor overlying the opening in the last mentioned partition and extending downwardly toward the

first mentioned floor of said compartment, and an air supplying pipe extending 10 through the wall of the hollow member and terminating above the said horizontal partition and under the space at the end of the inclined floor.

PERCIVAL W. MILES.
